SECTOR SCAN CIRCUIT

Merle A. Starr, Belmont, Mass., assignor, by mesne assignments, to the United States of America as represented by the Secretary of War

Application July 9, 1945, Serial No. 604,038

19 Claims. (Cl. 315—24)

1

This invention relates to electrical means for producing an output voltage or current which is a given function of an input voltage or current, and more particularly to electrical means whose output variation with respect to the input may be expressed as an equation of the second degree.

One object of this invention is to provide as an output from an electrical circuit a voltage whose magnitude varies as the sum (or difference) of first and second power functions of a variable input voltage. Another object of the invention is to provide simple, accurate, and reliable means for achieving a variation of the kind mentioned.

A further object of the invention is to provide means for changing the angle at which a radial sweep of a cathode ray tube electron beam emanates from the center of the cathode ray tube and yet maintain the amplitude of the sweep unchanged.

Other objects and advantages of the invention will appear more fully from the detailed description contained herein.

Referring now to the drawings:

Fig. 1 is a circuit diagram illustrating one embodiment of the invention;

Fig. 2 illustrates in diagrammatic form a yoke used in producing electromagnetic deflection of the electron beam of a cathode ray tube; and

Fig. 3 illustrates the vector field components resulting from currents in the coils of Fig. 2.

Referring now to Fig. 1, there is illustrated a preferred embodiment of this invention having a particular application which will appear more fully herein. A signal is fed through condenser 14, thus appearing across potentiometer 15, and a portion thereof is picked up by sliding contact 16 of potentiometer 15 and fed to grid 12 of vacuum tube 10, which has also a plate 11 and cathode 13. Cathode resistor 17 and plate resistor 18 are equal in value, and the alternating component of voltage at plate 11 is equal and out of phase with the alternating component appearing at cathode 13. The alternating components of plate and cathode voltages are fed through condensers 19 and 20, respectively, to grids 21 and 22 of tubes 23 and 24 across grid resistors 25 and 26. Cathodes 27 and 28 of tubes 23 and 24 are joined to sliding contact 29 of potentiometer 30 and thus have a variable cathode resistor in common. Resistors 31 and 32, chosen equal in this embodiment, are connected to a resistor 33 at their junction 34, and the other sides of resistors 31 and 32 are connected to plates 35 and 36, respectively, of tubes 23 and 24. Plate voltage supply is fed through resistor 33

so that resistor 33 forms a common plate load for tubes 23 and 24, and resistors 31 and 32 form separate plate loads for said tubes respectively. The outputs from this circuit are taken from junctions 35' and 36' of resistor 31 with plate 35 and resistor 32 with plate 36, respectively. Lead 37 conducts the output voltage from junction 35' to saw-tooth generator and amplifier 39, and lead 38 conducts the output voltage from junction 36' to saw-tooth generator and amplifier 40. Both of the saw-tooth generators and amplifiers 39 and 40 in this instance have like characteristics and are adapted to provide currents of saw-tooth form, rather than voltages of saw-tooth form, as it is contemplated that the output be used to provide electromagnetic sweep deflection of a cathode ray tube circuit. Furthermore, the saw-tooth generators and amplifiers 39 and 40 are adapted to respond with output currents the peak values of which are respectively modulated by the alternating voltage components of the signals applied through leads 37 and 38. This may be accomplished, for instance, by constructing saw-tooth generator and amplifier 39 (and similarly 40) of any standard saw-tooth generator coupled with an amplifier the peak current output of which is varied by the alternating voltage on lead 37.

Referring now to Fig. 2, there is illustrated a yoke of some magnetic substance such as soft iron wound by coils 42 and 43. As current i_1 from amplifier 39 passes through the windings of coils 42, flux within the yoke 41 has the direction shown by arrows 44 for the direction of current shown for i_1 . Thus, a leakage flux is produced inside the yoke having a direction and magnitude indicated by the vector H_1 . Likewise, a vector flux is produced by current i_2 in space quadrature with H_1 which will be termed H_2 , these vectors and the resultant vector H being shown in Fig. 3. However, saw-tooth generators and amplifiers 39 and 40 are in time-phase, and therefore vectors H_1 and H_2 are in time phase and it will be obviously sufficient to treat of their maximum values. Vectors H_1 and H_2 as shown are assumed equal in magnitude when no signal is introduced at grid 12 of tube 10 and consequently when no signal appears on leads 37 and 38. With a signal on grid 12 of tube 10, H_2' and H_1' are the component flux vectors caused by currents i_1 and i_2 , respectively, and H' is their resultant.

In radio echo detection apparatus, yoke 41 might be used on a cathode ray tube designed to indicate the disposition of objects in the horizontal plane about the apparatus as the center.

Since the displacement of the electron beam is proportional to the magnitude of the flux vector, although at right angles thereto, the maximum displacement of the electron beam corresponds to a maximum range scale indicated by the amount of radial deflection of the electron beam. When the resultant flux H' is shifted an angle A from resultant H , it is desirable to have the magnitude of H' remain the same as the magnitude of H , so that range representation will not be distorted or out of scale. The present invention affords a highly accurate means of obtaining such a result without rotating the yoke.

To analyze the variation desired in the modulating voltages on leads 37 and 38, we will let h represent the difference in absolute value between H_1' and H_2' . Referring to absolute values, if H_1 and H_2 are each increased and decreased respectively by h so that the new resultant H' is rotated an angle A from the old resultant H , then the following relations can be written:

$$(1) \quad H_1 - h = H_1(1 - \tan A)$$

$$(2) \quad H_2 + h = H_2(1 + \tan A)$$

However, a new resultant having these components is too great in magnitude, and to correct this discrepancy the right-hand terms of Equations 1 and 2 should be multiplied by $\cos A$. This gives:

$$(3) \quad H_1' = H_1(1 - \tan A) \cos A = H_1(\cos A - \sin A)$$

$$(4) \quad H_2' = H_2(1 + \tan A) \cos A = H_2(\cos A + \sin A)$$

If angle A is not large, it may be established that:

$$(5) \quad H_1' = H_1 \left[1 - A - \frac{A^2}{2} \right]$$

$$(6) \quad H_2' = H_2 \left[1 + A - \frac{A^2}{2} \right]$$

Therefore, currents i_1 and i_2 should have the form:

$$(7) \quad i_1 = K \left(1 - A - \frac{A^2}{2} \right)$$

$$(8) \quad i_2 = K \left(1 + A - \frac{A^2}{2} \right)$$

wherein K is some constant. This form of current is readily achieved by the invention if a signal is applied to grid 12 of tube 10 of an alternating component proportional to A . Assuming that currents flow in tube 10 in linear fashion with the signal voltage on grid 12 of tube 10, the signals at grids 21 and 22 of tubes 23 and 24 will be proportional to $-A$ and A respectively. The current flowing in tube 23, including second order terms, has the form:

$$(9) \quad i_3 = a - bA - cA^2$$

and the current flowing in tube 24 has the form:

$$(10) \quad i_4 = a + bA - cA^2$$

Let V represent the value of plate supply voltage to resistor 33, then the voltage V_1 at junction 35' has the form:

$$(11) \quad V_1 = V - a(2r_1 + r_2) - r_2 bA - c(2r_1 + r_2) A^2$$

and the voltage V_2 at junction 36' has the form:

$$(12) \quad V_2 = V - a(2r_1 + r_2) - r_2 bA + c(2r_1 + r_2) A^2$$

where r_2 is the value of resistor 31 or 32, and r_1 is the value of resistor 33.

Therefore, by choosing appropriate values for resistors 31 and 32 (which are equal to each other in this embodiment) and resistor 33, and by

choosing an appropriate bias through adjustment of the common cathode resistance 30, it is possible to obtain the proper ratio between the coefficients in Equations 11 and 12 so that these have the form of Equations 7 and 8, respectively, except for the constant voltage term and the inversion of sign. A change in sign of the alternating current components is obtained in amplifiers 39 and 40. In this fashion, currents i_1 and i_2 may be modulated so that vector H maintains a fixed magnitude, and angle A changes in accordance with the input signals to grid 12.

The system is particularly valuable where angle A changes rapidly up to values both positive and negative as high as $22\frac{1}{2}^\circ$, and represents the angle from a reference direction in the horizontal plane in radio echo detection apparatus. The electron beam of the cathode ray tube will accordingly change path in exact synchronism with the variations of the angle in the horizontal plane and yet maintain the proper range scale. A similar analysis shows that the input signal to grid 12 of tube 10 may be proportional to the tangent of the angle A , and a like approximation is possible, expressed in powers of the tangent of the angle. The invention is thus highly useful in depicting on a cathode ray tube complicated scanning motions in radio echo detection apparatus which involve rapid angular deviations from a given axis. For one such apparatus reference is made to copending application of Albert M. Grass, executed March 20, 1945, for scanning apparatus. In the "Palmer scan" motion mentioned in that case, a sine wave generator having a frequency of 30 C. P. S. may complete one cycle for each revolution of the antenna axis in its conical search pattern. This voltage is then proportional, with a high degree of accuracy for reasonably small angles of the axis of the cone with the horizontal plane, to the tangent of the angle which the projection of said axis on the horizontal plane makes with the axis of radiation. Thus, the sine wave generator is used to provide a signal proportional to $\tan A$, where A is the said angle of the axis of radiation with the axis of conical search pattern projected on the horizontal plane. Using an approximation correct to terms including $\tan^2 A$, it is readily shown that Equations 7 and 8 have the same form for $\tan A$, if A is small, as for A . That is, A may be replaced by $\tan A$ in all the Equations 7, 8, 11 and 12 when the signal is proportional to $\tan A$. With regard to design considerations which may be involved in the type of circuit disclosed herein, it is not essential that both plate voltages be utilized as outputs, nor that resistors 31 and 32 be equal. This was done in the present instance because the desired voltage variation for controlling the flow of current in the yoke coils is easily obtained by using both plate voltages. In general, the plate current through a tube may be considered in the form of a Taylor's expansion in terms of signal voltage, and the coefficients may be calculated or estimated by methods known in the art either experimentally or from tube characteristic curves. For example, see Principles of Radio Engineering, by R. S. Glasgow, p. 337 et seq., McGraw-Hill Book Co., Inc., 1936. Thus, once the principles of the invention are understood, it is not difficult to apply them in order to obtain a desired result, when the output voltage is taken from the plate of one tube which has part of its plate load in common with another tube, and the relation between the grid signals is known. Such devices as the variable cathode resistor in the circuit of Fig. 1 will assist in

obtaining the desired result by changing the ratio of the coefficients in the series.

Many variations will be apparent to those skilled in the art, and therefore it is not desired to restrict the scope of the appended claims to the precise embodiment as shown.

What is claimed is:

1. The method of obtaining a voltage which varies with a signal voltage in accordance with the terms of a second degree equation, said method comprising the steps of supplying said signal voltage 180° out of phase to the grids of two vacuum tubes, causing the current in both of said vacuum tubes to pass through a single resistance, and causing the current of one of said tubes to pass through a resistance which carries only the current passing through said one tube, the characteristics of said vacuum tubes in conjunction with the arrangement of said resistances being effective to produce a voltage which is substantially the sum of terms representative of a fixed voltage, terms proportional to the signal voltage, and terms proportional to the square of the signal voltage.

2. An electrical circuit for producing two output voltages, the first of which varies substantially in accordance with an input voltage, A, and equals the algebraic sum of $a+bA+cA^2$, and the second of which varies substantially in accordance with said input voltage, A, and equals the algebraic sum of $a-bA+cA^2$, a , b , and c being constants, said circuit including two vacuum tube amplifiers having a common cathode resistor connected to ground, two equal and separate plate loads, a source of positive potential, and a common resistor connecting said plate loads to said source of potential, paraphasing means for deriving from said input voltage, A, two equal components 180° out of phase from one another, means for impressing one of said components on the control grid of one of said amplifiers and the other of said components on the control grid of the other of said amplifiers, and utilization means coupled to the plate of each of said amplifiers, for utilizing the output voltages of said amplifiers.

3. A circuit as set forth in claim 2, wherein said utilization means comprises two sets of sawtooth current generators and amplifiers, and also including a magnetic yoke and two coils arranged thereon so as to produce two sets of lines of magnetic flux separated by 90° , each of said coils being coupled to the output of one of said sets of generators and amplifiers, whereby said coils produce two perpendicular magnetic fields having magnitudes varying, respectively, in accordance with the two equations set forth in claim 2.

4. A circuit as set forth in claim 3, wherein said paraphasing means is a paraphase amplifier having plate and cathode loads, the two 180° out of phase components being taken from said plate and cathode loads, respectively.

5. A circuit as set forth in claim 2, wherein said equal and separate plate loads are resistive means and said common cathode resistor is variable.

6. An electrical circuit for producing an output

voltage which varies substantially in accordance with an input voltage representing a given angle and equals the algebraic sum of a constant, a second constant multiplied by said input voltage, and a third constant times the square of said input voltage, said circuit including two vacuum tube amplifiers having a common cathode resistor connected to ground, two separate plate loads, a source of positive potential, and a common resistor connecting said plate loads to said source of potential, paraphasing means for deriving from said input voltage two equal components 180° out of phase from one another, means for impressing one of said components on the control grid of one of said amplifiers and the other of said components on the control grid of the other of said amplifiers, and utilization means coupled to one of said amplifiers, for utilizing the output voltages developed therein.

7. A circuit as set forth in claim 2, wherein said utilization means includes sawtooth current generator and amplifier means, and also including a circular magnetic yoke and two coils arranged thereon so as to produce two sets of lines of magnetic flux separated by 90° , one of said coils being coupled to the output of said amplifier means, whereby said coils produce two perpendicular magnetic fields the resultant of which varies in accordance with said given angle.

8. A circuit as set forth in claim 7 wherein said paraphasing means is a paraphase amplifier having plate and cathode loads, the two 180° out of phase components being taken from said plate and cathode loads, respectively.

9. A circuit as set forth in claim 6, wherein said plate loads are resistive means and said common cathode resistor is variable.

10. An electrical circuit for producing a magnetic field at a desired angle, comprising a first circuit for producing a voltage A, representative of the desired angle, a second circuit, connected to said first circuit, for generating an output voltage having the magnitude $a-bA+cA^2$, where a , b and c are constants, a third circuit connected to said first circuit, for generating an output voltage having the magnitude $a+bA+cA^2$, a pair of mutually perpendicular deflection coils, and means for generating currents in said two coils varying in accordance with said output voltages of said second and third circuits, respectively, whereby the resultant of the magnetic fields of said coils is at said desired angle.
